PAINT BUCKET HOLDER

Matt Spinello, Rockford, Ill.

Application September 6, 1955, Serial No. 532,469

1 Claim. (Cl. 248—211)

This invention relates to a bucket holder designed for quick and easy application to either side of a ladder and as quick and easy adjustment up or down on the ladder from one rung to another.

I am aware that many such holders have been proposed heretofore but most of them have been too complicated and expensive to manufacture at as low cost as an article of this kind should be obtainable so as to sell profitably. It is therefore the principal object of my invention to provide a bucket holder which, while affording all of the advantages of prior designs, is of only two piece construction and can be produced at much lower cost to sell at a price most people would be willing to pay for this kind of item.

In the drawing:

Fig. 1 is a perspective view of a portion of a ladder showing a bucket holder made in accordance with my invention applied thereto on the right-hand side, and also indicating in dotted lines how it is also applicable on the other side, and

Figs. 2 and 3 are a side view and front view of the bucket holder as it appears removed from the ladder, portions of the ladder being indicated in dotted lines.

The same reference numerals are applied to corresponding parts in these three views.

Referring to the drawing, the bucket holder of my invention is indicated generally by the reference numeral 5 and consists of only two parts, namely, a channel shaped sheet metal frame member 6, and a wire hanger 7 assembled thereon, the frame member 6 being adapted to fit on either side rail 8 of a ladder, and the hanger 7 being adapted to be hung by means of its hook-shaped upper end 9 on any one of the rungs 10 of the ladder and to support a paint bucket 11 or the like on its hook-shaped lower end 12. The sheet metal frame member 6 has on one side 13 thereof a longitudinal flange 14 bent inwardly to engage the inner side of the side rail to prevent outward displacement of the frame member. The flange 14 is short enough to clear the rungs 10, as plainly shown in Figs. 1 and 2. The other side 15 of the frame member has no flange on it. The frame member fits on the side rails 8 loosely enough so that it can be easily applied to or removed from a side rail and is slidably freely lengthwise thereof when applied. The wire hanger 7 is pivotally connected by its straight elongated intermediate portion 16 with the frame 6 longitudinally of the middle of the wide web portion 17 in an elongated half-round bearing 18 embossed from the web. The hook 12 is formed by bending outwardly the protruding lower end portion of the straight wire after the hanger 7 is assembled on the frame by entering the straight portion 16 in bearing 18. Hook 12 then serves the double purpose of supporting the frame 6 against slipping downwardly on the side rail 8 and also providing support for the bucket 11 when its bail 19 is applied to the hook 12 as seen in Fig. 1. Endwise movement of hanger 7 relative to frame 6 is limited in one direction

2

by hook 12 and in the other direction by a right angle bent portion 20 which constitutes one arm of a U-shaped portion 21 disposed in a substantially horizontal plane substantially normal to the straight portion 16 which reaches around the front or back of the side rail 8, depending on which side of the ladder receives the bucket holder, from the bearing 18 on the outer side to the hook 9 on the inner side, the hook 8 being integral with the other arm of the U-shaped portion 21 in a vertical plane substantially at right angles to the vertical plane of the hook 12. The U 21 is of ample length and width in relation to the dimensions of the side rails 8 so that it is easy to swing the hook 9 into and out of place over a rung 10, the hanger 7 pivoting, of course, in the bearing 18 in these movements.

In operation, the bucket holder is applied to the ladder on either side rail 8 by first applying the frame 6 to the side rail and then swinging the hook 9 into position over the selected rung 10 and allowing the device to drop down so that the hook 9 is engaged on the rung. The hook 12 is then ready to receive the bail 19 of a paint bucket 11 or other container to be hung on the bucket holder 5. When the painter wants to move the holder up or down he removes the bucket 11 and disengages hook 9 and slides frame 6 on side rail 8 to the new position and applies hook 9 again on a rung there, after which the bucket 11 can be replaced on hook 12.

It is believed the foregoing description conveys a good understanding of the objects and advantages of my invention. The appended claim has been drawn to cover all legitimate modifications and adaptations.

I claim:

A device of the character described comprising an upright elongated one-piece sheet metal channel frame member for application to the outer side of either side rail of a ladder, said channel frame member having a web portion and parallel side walls and an integral elongated half-round bearing portion projecting from the middle of the web portion longitudinally thereof which is open at both ends, one of said side walls having an inwardly bent edge portion parallel to the web portion whereby to define a channel wherein to receive one longitudinal edge portion of the ladder side rail, and a hanger made of one elongated piece of wire having a straight elongated pivot portion intermediate its ends received with freedom for oscillation in the aforesaid bearing and protruding from the opposite ends thereof, one protruding end portion being bent to define an upwardly facing hook onto which to hang a container, the other protruding end portion being bent to define a downwardly facing hook in a plane in inwardly spaced parallel relation to the web portion of said channel frame member, the last mentioned protruding end portion between the pivot portion and the downwardly facing hook being bent to define a U in a substantially horizontal plane wherein to accommodate the other longitudinal edge portion of the ladder side rail, one arm of the U being connected to the upper end of the pivot portion, and the other arm of the U being connected to the downwardly facing hook.
